UNITED STATES PATENT OFFICE

170,160

CHILD'S SCOOTER

Ferdinand R. Minozzi, Yonkers, N. Y.

Application January 27, 1953, Serial No. 23,318

Term of patent 14 years

(Cl. D34—15)

To all whom it may concern:

Be it known that I, Ferdinand R. Minozzi, a citizen of the United States, residing at Yonkers, county of Westchester, State of New York, have invented a new, original, and ornamental Design for a Child's Scooter, of which the following is a specification, reference being had to the accompanying drawing, forming part thereof, wherein

Figure 1 is a side elevational view of a child's scooter embodying my new design;

Figure 2 is a top plan view thereof;

Figure 3 is a front elevational view thereof; and

Figure 4 is a rear elevational view thereof.

I claim:

The ornamental design for a child's scooter, as shown.

FERDINAND R. MINOZZI.
